WIRELESS RECEIVING SYSTEM

Application filed September 22, 1926. Serial No. 137,038.

The present invention relates to improvements in the construction, arrangement and connections of electrical apparatus for wireless reception. The object of this invention is to provide a receiver having at least one stage of radio frequency amplification ahead of the detector stage, the stabilization of which radio frequency amplifying stage is under the control of the operator, is very easily adjusted and provides an extremely stable radio frequency amplifying unit over a wide band of broadcast frequencies, yet at the same time permitting very high amplification at every frequency for which the receiver is designed.

The detector may be of any known type and amplification preceding the detector stage may be obtained by audions or vacuum tubes adapted to be operated on either alternating or direct current employed for the direct electrical heating of the electron-emitter element or for indirectly heating such element.

An important feature of the invention resides in the provision of an independent stabilizing circuit which connects the grid and electron-emitter element of an audion which is to be stabilized, this stabilizing circuit being so arranged as to exclude all batteries, or other current supplying means, condensers, coils and other electrical elements through which the current of other essential circuits must flow, it being necessary only to qualify this statement to the extent that the stabilizing circuit may be said to make use of the simple conductors or leads connected to the audion in common with other circuits. It will be noted, however, that as to such conductors there is no appreciable impedance or reactance which could cause any undesirable interaction between the stabilizing current and the current flowing in any other circuit. This isolation of the stabilizing circuit has been found to give greatly improved results as compared with stabilizing systems wherein the stabilizing or neutralizing circuits have included electrical elements, such as batteries, condensers, etc. which provide a common path for both the stabilizing current and also the plate or grid currents of the audi-

ons. The stabilizing system according to the present invention is not critical in adjustment and permits a very smooth and gradual regulation of amplification. Furthermore, when adjusted to obtain practically the maximum amplification the circuit is not in the usual critical condition, and severe static and other stray disturbances do not cause the audion circuits to break into uncontrolled oscillation which ordinarily gives rise to the familiar squeal or heterodyne note. In the operation of the receiver it is also observed that practically no greater movement of the stabilizing control is necessary to stop uncontrolled oscillation than is required to start it, so that if the critical setting is exceeded the objectionable oscillation is stopped by a very slight reverse movement of the control. This characteristic is of material advantage in picking up very weak signals which, in the usual receiver employing regeneration in the radio frequency stage, are only audible at the most critical setting of the regeneration control. For such receivers the weak signals become inaudible when the control is turned back a sufficient distance to check excessive oscillation once the circuit has "spilled over", whereas in the present apparatus the signal becomes audible practically at the instant that such oscillation ceases. This unique characteristic may perhaps be best described as one of flexibility of control, since it renders simple and facile, an adjustment which has hitherto required considerable skill and nicety of manipulation.

The radio frequency amplifying circuit hereinafter to be particularly described is applicable to a wide variety of wireless receiving apparatus. The method of stabilizing the radio frequency amplifying circuit is applicable to receivers employing a plurality of radio frequency amplifying stages before the detector stage.

The invention further contemplates means for effectively by-passing radio frequency current around the plate current supply of the radio frequency amplifying stage, which current supply is common, at least in part, to the filament plate circuits of other "audions" in the receiver, whereby to eliminate as far

as possible the presence of radio frequency current in the audio amplifying circuit.

It is well understood that in radio frequency amplifying circuits employing audions or vacuum tubes, much difficulty is experienced in preventing uncontrolled oscillation and at the same time maintaining a high amplification. This difficulty is due in part to the capacity effects between the elements 5 of the vacuum tube itself and also to the capacity and magnetic coupling between the various coils and leads which necessarily constitute a part of the receiving circuit. Because of the impossibility of effectively isolating various elements of the receiving circuit, energy is transferred from one part of the circuit to another in a manner which in an efficient receiver almost inevitably results in a condition of instability, the circuit having a pronounced tendency to break into self-sustained oscillation. This tendency must be counteracted in order to permit of the reception of broadcasting.

A number of systems have already been devised for the purpose of stabilizing the radio frequency amplifying stages. One method is to control the grid potential by means of a potentiometer, another to control the brilliancy of the filament in the vacuum 25 tube. According to another system a tickler coil inserted in series with the filament plate circuit is inductively related to the input circuit in such manner that a negative feedback takes place, this feedback being controlled by 30 varying the coupling between the two circuits to effectively suppress local oscillations in the radio frequency amplifying tube. Still another method contemplates the suppression of local oscillation in the radio frequency 35 stages by tapping the secondary winding of the interstage transformer coupling any two successive stages, such as the first and second radio frequency amplifying stages or the second amplifying stage and the detector, 40 and leading a portion of the energy developed in the secondary winding of such transformer back through a small condenser to the grid of the tube which feeds the transformer. This latter method of stabilization 45 characterizes the neutrodyne circuit in which recourse is had to a comparatively loose coupling between the transformer windings for the purpose of reducing the tendency toward self-sustained oscillation to a point where 50 a neutralizing condenser, which has been set at the factory, will suffice to prevent such oscillation over a predetermined band of frequencies for which the receiver is designed. Such loose coupling necessarily involves a 55 loss of efficiency. Other stabilizing methods are known, such as inserting resistances in various parts of the radio frequency circuit or inductively coupling to such circuits various energy-absorbing means, but such 60 methods are not efficient and generally result

in losses which render the radio frequency amplification stage of relatively small value. In practice it has been found, generally speaking, that stability and ease of control of the radio frequency amplifiers have been obtained at the expense of amplification and sharpness of tuning.

The present invention provides a receiving apparatus having one or more stages of radio frequency amplification in which effective stability is obtained with relatively low losses in the amplification, the receiver at the same time having unusually high selectivity. While more than one radio frequency amplifying stage may be employed, this is not necessary because with an efficient antenna the amplification obtainable in a single stage, according to the present invention, is as high as the static level will permit. That is to say, a single stage of radio frequency amplification will satisfactorily amplify a signal so weak that it is almost useless because of the relative intensity of static disturbances and other "strays" which are present under the most favorable receiving conditions. It will therefore be understood that the efficiency of the present system is exceedingly high since the great majority of modern receivers require at least two radio frequency stages, and in many instances more than two stages to obtain this result. The circuit, furthermore, possesses the highest selectivity theoretically obtainable because it is possible to so sharply tune the receiver that portions of the "side bands" in radio broadcasting are cut out thereby limiting the range of audible sounds which can be received. For radio broadcast reception it is therefore not desirable to make use of the full selectivity available in this receiver. The radio frequency amplifying circuit hereinafter to be described may be combined with any detector and audio amplifying system. However, in its preferred embodiment, in a radio broadcast receiver for the wave lengths now employed by the greater number of broadcasting stations, the radio frequency amplifying circuit is combined with a detector circuit having the usual "hard" vacuum tube as a detector and a three-stage resistance coupled audio amplifier.

Further objects of the invention will hereinafter be pointed out in connection with the detailed description of the invention, reference being had to the accompanying drawings, in which,

Figure 1 is a circuit diagram of a radio receiver employing one stage of radio frequency amplification, a detector stage and three resistance coupled audio amplifying stages.

Fig. 2 is a perspective view of the special three winding transformer and stabilizer which couples the radio frequency stage to the detector and serves as a source of stabiliz-

ing energy for the radio frequency amplifying circuit.

Fig. 3 is a circuit diagram of a receiver employing two stages of tuned radio frequency and a detector, no audio frequency amplification being shown.

In the embodiment illustrated in Figure 1 a radio broadcast receiver according to the present invention comprises a radio frequency amplifying stage generally designated by R. F., a detector circuit D and three stages of resistance coupled audio amplification designated respectively as A. F.¹, A. F.² and A. F.³. An inductance L₁ shunted by a variable condenser C₁ constitutes the tuned circuit of the radio frequency amplifying stage. The inductance coil L₁ is preferably tapped at three points towards its lower end, as illustrated at 1, 2 and 3, to provide for a direct connection of the antenna at one of the three points. This provides what may be termed a semi-tuned antenna circuit, the incoming energy from the antenna a passing through more or less of the tapped inductance L₁ and thence directly to the ground g. The antenna connection with inductance L₁ at various points may be effected by any suitable switching device such as a three point switch S, the contacts of which are connected to the three taps referred to. The elements which distinguish the present radio frequency amplifying circuit from other known devices are incorporated in what may be termed a combination radio frequency transformer and stabilizing unit diagrammatically indicated in Figure 1 at P, S and S'. The assembly of this unit as it appears in perspective, is shown in Fig. 2. This combination unit comprises a primary winding P which is connected as shown directly in the filament plate circuit of the radio frequency tube, a secondary winding S preferably closely coupled to said primary winding and a stabilizing winding S' inductively related to both the said primary and secondary windings.

A unit which has been found highly satisfactory comprises a supporting tube 4 upon which is successively wound the three windings S, P and S' respectively. The primary and stabilizing windings are preferably placed near the filament or low potential end of the secondary winding. The windings are preferably wound in the same direction and connected to the various leads, as indicated in the diagram. It will be understood that the description of this transformer and stabilizing unit is in certain respects merely illustrative and that other arrangements whereby three windings may be inductively related and employed for the purposes herein specified falls within the scope of my invention. For example, it has been found that satisfactory results may be obtained by winding the stabilizing winding directly on the sec-

ondary, and winding the primary on top of the said stabilizing winding. Except for the mechanical difficulties of fabricating the unit, the stabilizing winding and primary may be disposed within the secondary. Furthermore, it is not essential that the primary and stabilizing windings be placed close to the filament or low potential end of the secondary winding, but may be located some distance therefrom. It is important, however, that the primary and secondary windings be closely coupled, and for this reason they are wound in such manner as to be radially overlapping and are not separated by a large air gap as is customary in the majority of commercial receivers. To obtain maximum coupling it is important that the high potential terminals of the primary and secondary windings be of the same polarity, as will hereinafter more fully appear. In the past it has been customary to arrange the transformer windings so that the high-potential terminals are of opposite polarity, with the particular object of reducing the coupling so as to achieve a condition of automatic stability over a predetermined range of operating frequencies but at the sacrifice of efficient amplification. The windings P and S, considered alone, constitute the radio frequency transformer whereby the output of the radio frequency tube r is delivered to the detector d. In addition to this usual transformer arrangement, however, a third winding, which I have designated a stabilizing winding S', is closely coupled to the two windings P and S constituting the radio frequency transformer. There is induced in this winding a fluctuating potential which is dependent upon the combined magnetic flux of the two coils P and S.

The upper end of the stabilizing coil S' is connected to the filament lead of the radio frequency tube r, as shown in Figure 1. The lower end of the stabilizing coil is connected through a small variable condenser C₂ with the grid lead of this tube. The upper or high-potential terminals of the primary winding P and secondary winding S are connected respectively to the plate and grid leads of the vacuum tubes r and d, while the low-potential terminals of said windings are connected to the filament systems of said tubes. The lower terminal of the secondary winding S connects directly with the filament system while the lower end of the primary P is connected therewith through the plate current supply, the terminals employed for this connection being marked respectively R. F. and "A"—"B" in Fig. 1. It will thus be seen that the plate terminal of the primary winding P and the grid terminal of the secondary winding S are disposed relatively toward the same end of the windings, i. e., toward the high-potential ends, and said terminals are of the same polarity. This re-

sults in obtaining a much closer coupling between the primary and secondary windings than if their high-potential ends were of opposite polarity. This very close coupling permits of the maximum transfer of energy from primary to secondary windings and accounts in considerable measure for the remarkably high efficiency of the receiver according to the present invention. This close coupling, 10 in the absence of the variable control of stabilization as herein provided, would render the circuit impossible to stabilize throughout the usual range of broadcast frequencies unless one or another of the previously known energy-wasting devices, or "lossers" as they are generally referred to, were employed. Obviously the use of any such device would defeat the object of my invention which is to achieve the maximum 15 efficiency of output from the number of vacuum tubes employed. The large number of tubes in modern receivers is to a considerable extent necessitated by the inefficiency of the circuits, efficiency having been sacrificed to 20 obtain stable operating characteristics.

In the circuit according to the present invention high efficiency is achieved, and controllable stabilizing means are provided which permit the utilization of such efficiency 25 to the fullest extent over the entire range of broadcast frequencies whenever weak signals are to be picked up. In other words, instead of providing a receiver that wastes a sufficient amount of energy to render the 30 circuit automatically stable at all frequencies in the broadcast band, I utilize a circuit in which the efficiency is preferably such that automatic stabilization can not be achieved 35 at all broadcast frequencies and provide 40 means for adjusting the stabilization in accordance with the frequency which is being received. This adjustment is unnecessary when receiving strong local signals because the tubes are then only required to operate 45 at low efficiency and the tendency toward self-sustained oscillation can be effectively suppressed by reducing the filament voltage 50 in the detector and radio frequency stages. The proper value for the windings P, S and 55 S' once having been determined, the combination transformer and stabilizing unit generally designated by A, is preferably assembled as a fixed part of the apparatus, no 60 adjustment being thereafter required in the inductance or coupling of the three elements thereof. It will be understood that wherever 65 the term filament is employed herein the word is used generically to indicate the electron 70 emitter element which cooperates with the plate of the vacuum tube to provide a path for the plate current, the flow of which is regulated by the grid potential in a well-known manner. The filament need not be 75 60 in the form of a wire nor need it be heated

by current which passes directly therethrough.

The stabilizing winding S' is so related to the transformer windings P, S that there will be induced in the former a fluctuating current, which, if properly controlled by the variable capacity C₂, will effectively oppose the action of electrostatic coupling between the elements of the vacuum tube and stray coupling between other portions of the receiving circuit, whereby the capacity for self-sustained oscillation within the circuit may be entirely eliminated.

In properly designed apparatus according to the present invention, the control of amplification through the adjustment of the stabilizing condenser C₂, while not critical, is extraordinarily effective. It is possible for one who is not skilled in the handling of receiving apparatus to obtain practically the maximum possible amplification, taking full advantage of the inherent amplifying power of the radio frequency stage. As is well understood in most radio receiving apparatus, the adjustment of the control which suppresses self-sustained oscillations is very critical. To obtain anything like efficient results the control must be adjusted to a point very close to the point of oscillation and yet must not reach this point, or the signal which is desired will be obliterated. By virtue of the novel design and relationship of the various elements in the present receiving apparatus, an unusually high degree of inherent stability of the radio frequency circuit is obtained without recourse to wasteful energy-absorbing means. At the same time the circuit can be brought practically to the peak of possible amplification and will remain in continuous operation very close to this peak regardless of disturbances such as heavy "strays" or wide fluctuations in signal intensity without danger of "spilling over" or breaking into self-sustained oscillation. Such oscillation practically destroys the broadcasting which it is desired to receive, and not only gives rise to objectionable squeals and howls at the receiver, but in most instances, re-radiates oscillating energy from the antenna, which is highly disturbing to neighboring receivers.

The explanation which at this time seems best to account for the unusual operating characteristics of this receiver is the fact that the stabilizing coil S' is conductively independent of either the filament-plate circuit of the radio frequency tube or the grid circuit or connections therewith in the detector stage. In the well known neutrodyne circuit the stabilizing energy which is fed back to the grid of the radio frequency tube is tapped off from a point between the ends of the secondary winding of the radio frequency transformer. As a consequence of this, whatever current changes occur in the secondary of the transformer which feeds the

detector are conductively carried to the neutralizing condenser and thence to the grid of the radio frequency tube.

In another well known system hereinbefore mentioned, energy is fed back to the grid of a radio frequency tube inductively through a tickler coil which is directly and conductively included in the filament plate circuit of the radio frequency tube.

10 I am not aware of any system in which a conductively independent stabilizing winding is inductively coupled to the primary and secondary of a radio frequency transformer and is utilized as a source of energy supplied 15 to the grid or other related parts of the radio frequency circuit whereby to counteract the inherent tendency of a tuned vacuum tube circuit to generate self-sustained oscillations.

Because of the effectiveness of the stabilizing control it has not been found necessary to reduce the number of turns on the primary winding P whereby to reduce the tendency toward oscillation, with a consequent loss of efficiency in the transfer of energy between 25 the primary and secondary windings of the transformer. This is a well known method of obtaining stability in the radio frequency amplifier but results in low efficiency.

The detector stage of the receiver illustrated in Figure 1 differs from usual practice in certain respects. The fixed capacity C_5 is shunted across the "B" battery supply to the plate circuit and also the resistance element or resistor R_1 of the audio amplifying 35 circuit. The transformer secondary S which feeds the detector grid forms an integral part of the combined transformer and stabilizing unit A , as has hereinbefore been pointed out. The secondary winding S is 40 tuned in the usual manner by a variable condenser C_3 . Detection is accomplished preferably by the usual hard vacuum tube, in the grid lead of which is placed a grid condenser C_4 around which is shunted a high resistance 45 grid-leak R . The detector stage in the preferred embodiment of my invention is non-regenerative and is so designed that self-sustained oscillations can not be set up therein. It has been found difficult to eliminate distortion where any high degree of regeneration 50 is employed in the detector circuit, and the present radio frequency amplifying circuit is so efficient that further amplification in the detector is not necessary.

55 To eliminate, as far as possible, distortion of any kind, and at the same time secure ample volume for ordinary loud speaker operation, three stages of resistance coupled audio amplification are preferably used. The first 60 two audio frequency amplifying tubes a^1 and a^2 may be of the usual 201-A or 301-A type. The third audio amplifying tube a^3 is preferably a tube of higher capacity or what is now 65 termed a power tube, which is capable of handling relatively large energy for effective

loud speaker operation without danger of overloading and consequent distortion of the broadcast reception. The design of the resistance coupled audio amplifier, generally speaking, corresponds with usual practice. 70 There are two features which depart from known methods, however. One of these is the connecting together the filament controls of the detector and audio frequency amplifying tubes. This has not, to my knowledge, been 75 possible heretofore. Because of the unusual stability of the present receiver it is feasible to connect the filaments of any or all of the vacuum tubes in the system together and control the current flowing through such tubes 80 by a current limiting device common to all, no individual filament control being required whereby to independently vary the filament brilliancy of the detector tube with respect to the audio frequency tubes. In the construction illustrated in Figure 1 a single automatic ballast resistance R_2 is employed to control the filaments of the detector and the first and second audio frequency amplifying tubes. A 85 second ballast resistance R_3 is employed to control the filament of the power tube in the third audio frequency stage because of the fact that it is often desirable, when great volume is not required, to cut out the power tube 90 and operate only on two stages of resistance 95 coupled audio amplification. The radio frequency tube may be controlled by a single resistance such as R_2 in common with the detector and audio frequency amplifying tubes. However, an independent variable resistance 100 R_3 is preferably employed.

No independent switches are provided for the various tubes, all of the tubes being under the control of the two automatic circuit jacks J_1 and J_2 respectively which are connected 105 as indicated in the diagram Fig. 1. By this arrangement the receiver may be operated with or without the last stage of audio frequency amplification in which the power tube a^3 and four tube or five tube operation is obtained simply by inserting the phone plug in the desired jack. If the reproducer is not 110 plugged into either jack none of the tube filaments is lighted. If the plug is inserted in the first jack J_1 the first four tubes r , d , a^1 115 and a^2 are lighted, the power tubes a^3 receiving no "A" battery current. If the plug is inserted in the second jack J_2 the filaments of all five tubes are lighted and the circuits connected for five tube operation. This arrangement has the advantage of eliminating the filament controlling switch or switches which ordinarily operate independently of the telephone or loud speaker jacks. By this arrangement the operator knows at a glance 120 whether any of the tubes are lighted or not by simply observing whether the plug is inserted in either of the jacks. One need not be near the apparatus to tell this. As long as the loud speaker, for example, is plugged in 125 130

to the receiver, the receiver is in operation, and when the loud speaker plug is withdrawn, the set is out of operation and drawing no current from the batteries. This greatly 5 reduces the possibility of inadvertently leaving a filament control switch closed, with consequent waste of both "A" and "B" battery current when the receiver is not in use.

10 A by-pass condenser C_6 of large capacity is shunted across the section of the "B" battery which supplies the plate voltage to the radio frequency tube r , thereby eliminating the bad effects of battery resistance in the radio frequency amplifying circuit, and to a large extent 15 reducing the radio frequency component of energy in the audio amplifier. This fixed capacity C_6 adds materially to the effectiveness of the radio frequency amplification although the circuit will operate satisfactorily 20 without it.

A fixed condenser C_7 is preferably shunted across the entire block of "B" batteries feeding the plate circuit of the power tube a^3 and also the jack J_2 feeding the reproducer. That 25 is to say, the condenser serves as a by-pass around both the loud speaker and "B" battery. The position of capacity C_7 in the circuit is a departure from usual practice.

30 In constructing a receiver according to the present invention the coil L_1 is disposed with respect to the combination transformer and stabilizing unit A in such manner as to reduce as far as possible stray coupling, either electromagnetic or electrostatic, between 35 the two. This is accomplished by placing the two elements some distance apart and with their magnetic axes at right angles to each other. Stray coupling may, of course, be further reduced by shielding the elements in individual metallic cages, which are preferably grounded, but the circuit does not require such shielding in order to obtain stability.

40 The stabilizing method hereinbefore described is, as has already been pointed out, applicable to multistage radio frequency amplification, a modified circuit incorporating two stages of tuned radio frequency amplification being diagrammatically illustrated 45 in Fig. 3. It will be observed that the additional stage of radio frequency amplification follows usual practice except that a second combination radio frequency transformer and stabilizer unit A' is interposed between 50 the two stages of amplification. The other details of the circuit need not be described as they follow practice which is entirely familiar to those skilled in the art.

To render the disclosure of my invention 55 more complete and to facilitate its practical application by those skilled in the art, I will give the characteristics of the various elements which I have found to give the best results for wave lengths between 250 and 60 500 meters. The tuning coil L_1 and the com-

bined transformer and stabilizing coil A in the embodiment shown in Fig. 1 are both wound on cylindrical forms approximately three inches in diameter. The tuning coil L_1 is made up of 57 turns, the coil being 70 tapped at the third, seventh and eleventh turn respectively, for rough antenna tuning. The combination transformer and stabilizing unit shown in perspective in Fig. 2 comprises a primary winding P of ten turns, a secondary winding of 59 turns and a stabilizing winding of 9 turns. The values for the other elements in the circuit, are as follows:

C_1	.00035 microfarad	80
C_2	about 15 micromicrofarads (commercially known as a midget condenser)	80
C_3	.00035 microfarad	85
C_4	.00025 microfarad	85
C_5	.002 microfarad	85
C_6	1 microfarad	85
R	2-5 megohms	95

The values of the resistances in the audio frequency amplifying circuit will, of course, vary with the type of tube used, as well as 90 the filament control resistances, which may be of the manually variable type or the automatic ballast resistance. If a power amplifying tube is employed in the last audio frequency stage, a "C" battery X should be employed in accordance with the characteristics 95 of the tube used.

The operation of the five tube receiver shown in Figure 1 is very simple, only two of the variable controls requiring adjustment 100 for local reception. If extremely weak signals are to be received, adjustment of the stabilizing control is required and also approximate tuning of the aerial circuit by the selection of the tap on the inductance L_1 best 105 suited to the desired wave length. To place the set in operation it is only necessary, as before described, to insert the loud speaker plug or phone plug, as the case may be, in either jack J_1 or J_2 depending upon whether 110 four tube or five tube operation is desired. If local stations only are to be received, the stabilizing condenser C_2 is set in a position to insure freedom from local self-sustained 115 oscillation in the radio frequency stage and the various stations may be tuned in by simply adjusting the two variable condensers C_1 and C_2 , the dial settings of which for any given frequency will be substantially the same. The 120 dials of these condensers may be frictionally coupled together in accordance with known practice whereby the two condensers will be adjusted in unison. No attention need be paid to the filaments of the detector and audio frequency amplifying tubes, as in the present receiver. These tubes are controlled by automatic filament ballast resistances R_2 and R_3 . The rheostat R_4 controlling the filament 125 of the radio frequency tube or audion r , once adjusted to give the best results, need

not be again altered so long as the filament voltage supply remains substantially the same.

To pick up very weak signals the proper tap on inductance L_1 is selected for the desired frequency and the condenser C_2 is adjusted to a position in which a beat note is heard, when the condensers C_1 and C_3 are set for the desired frequency. This beat note is due to the self-sustained oscillation within the radio frequency stage in combination with the carrier wave which is being received. When the tuning condensers C_1 and C_3 are adjusted to a position which gives the lowest frequency beat note, the stabilizing capacity control C_2 is moved back to a position where the beat note disappears, indicating that self-sustained oscillation within the receiver has been suppressed. Once these various adjustments for a given station have been determined, the station can always be again picked up on its characteristic frequency by setting the various controls in the determined positions. That is to say, each of the controls can be logged for any given frequency, and by placing the controls in the logged positions the receiver will be accurately tuned for this frequency. This statement holds true for the stabilizing control effected through the adjustment of condenser C_2 , which is provided preferably with a graduated dial as are the ordinary tuning condensers.

In the appended claims the term audion is employed to designate any form of thermionic valve in which is included an electron emitting element, a positively charged plate or collector for the electrons, and a grid controlling the flow of electrons from said element to said plate; and the term filament is employed in the generic sense to indicate any heated electron emitting element whether it be heated directly by the action of an electric current or otherwise.

While the invention in its preferred embodiment has been described and illustrated, it is to be understood that the invention may be modified and otherwise embodied without departing from the spirit of the invention, as set forth in the following claims.

What I claim is:

1. In a wireless receiving apparatus employing audions, a stage of tuned radio frequency amplification, a detector stage, a transformer comprising primary and secondary windings inductively coupling said stages together, the said primary and secondary windings being so arranged that the high-potential terminal of the primary winding is of the same polarity as the high-potential terminal of the secondary winding, and an independent stabilizing winding in the magnetic field of said transformer, one end of said winding being connected directly to a filament lead of the radio frequency

audion and the other end of said winding being connected through a variable condenser to the grid of said audion.

2. In a wireless receiving apparatus employing audions, a plurality of tuned stages of radio frequency amplification, a transformer comprising primary and secondary windings inductively coupling successive stages together, the said primary and secondary windings being so arranged that the high-potential terminal of the primary winding is of the same polarity as the high-potential terminal of the secondary winding, and an independent stabilizing winding and circuit therefor which does not include any winding or condenser constituting a part of the tuned input circuit of any of said stages, said winding being inductively coupled to the windings of said transformer, and adapted to feed back energy directly to the grid of the audion of the first of any two successive stages of amplification and in a direction to suppress self-sustained oscillations in such stage, the connections being such that the resistance and stray field pick-up of the filament plate current supply means is excluded from the said circuit of the stabilizing winding.

3. In a wireless receiving apparatus employing audions, a plurality of stages of radio frequency amplification, a transformer comprising primary and secondary windings inductively coupling successive stages together, the said primary and secondary windings being so arranged that the high-potential terminal of the primary winding is of the same polarity as the high-potential terminal of the secondary winding, and an independent stabilizing winding inductively coupled to the windings of said transformer, a condenser in series with said stabilizing winding, the said stabilizing winding and condenser being connected between the grid of the audion of the said first stage of amplification and a filament lead of such audion by simple metallic conductors.

4. In a wireless receiving apparatus, a stage of radio frequency audion amplification including the primary winding of a radio frequency transformer, said winding comprising a part of the filament-plate circuit of said stage, the secondary winding of said transformer forming a part of the tuned grid circuit of the next succeeding audion, the said primary and secondary windings being so arranged that the high-potential terminal of the primary winding is of the same polarity as the high-potential terminal of the secondary winding, and an independent stabilizing winding external to either of the said circuits but inductively coupled to at least one of said transformer windings and adapted to feed back stabilizing energy directly to the grid of said radio frequency audion through an independent circuit which

includes a variable condenser, and in each circuit there is no winding or condenser which would constitute a part of a tuned input of the said first mentioned audion 5 stage whereby to suppress self-sustained oscillations in said stage.

5. In a wireless receiving apparatus employing an audion in the radio frequency amplifying stage, a transformer comprising primary and secondary windings conductively coupling the stage of radio frequency amplification with the detector circuit, the said primary and secondary windings being so arranged that the high-potential terminal 10 of the primary winding is of the same polarity as the high-potential terminal of the secondary winding, an independent stabilizing winding in the magnetic field of said transformer, a variable condenser in series 15 with said stabilizing winding, the said stabilizing winding and condenser being connected directly between the grid of the audion of the said radio frequency amplifying stage and the positive filament lead of such audion.

20 6. In a wireless receiving apparatus employing audions, two transformer connected audion stages, the transformer having its primary winding in the plate circuit of the first audion and its secondary winding in 25 the grid circuit of the second audion, the said primary and secondary windings being so arranged that the high-potential terminal of the primary winding is of the same polarity as the high-potential terminal of the secondary winding, and an independent stabilizing winding inductively related to said 30 transformer windings, a variable condenser connected in series with said stabilizing winding, the last mentioned winding and condenser in series therewith providing a bridge circuit between the grid and electron 35 emitter element of the first audion, and this bridge circuit being disposed so as not to include the plate current-supply means, or 40 any winding or condenser through which the plate current is directly applied.

45 7. An electric circuit arrangement for stabilizing transformer coupled audions, comprising a primary winding connected between the plate and electron emitter of one audion, a secondary winding connected between the grid and filament of a second audion, and an independent stabilizing winding and condenser connected in series 50 between the grid and electron emitter of said first-mentioned audion, the said primary and secondary transformer windings being wound in the same direction and radially 55 overlapping, the plate terminal of the primary winding and the grid terminal of the secondary winding being disposed relatively 60 toward the same end of said respective windings.

65 8. In a wireless receiving apparatus employing audions, a stage of tuned radio fre-

quency amplification, a detector stage, primary and secondary windings inductively coupling said stages together, said primary and secondary windings being so arranged that the high-potential terminal of the primary winding is of the same polarity as the high-potential terminal of the secondary winding, and a stabilizing winding and variable condenser connected in series between the grid and electron emitter of the audion in the said radio frequency stage, said variable condenser being provided with a manual control adapted to be readily adjusted in the manner of a tuning control according to the frequency of the impressed oscillating current whereby to obtain the requisite degree of stabilization at various frequencies.

70 9. An electric circuit arrangement for stabilizing transformer coupled audions, comprising a primary winding connected between the plate and electron emitter of one audion, a secondary winding connected between the grid and electron emitter of a second audion, the said primary and secondary transformer windings being so related that the high-potential terminal of the primary winding is of the same polarity as the high-potential terminal of the secondary winding, an independent stabilizing winding and variable condenser connected in series between the grid and electron emitter of said first 75 mentioned audion, and a manual control for said variable condenser adapted to be readily adjusted in accordance with the frequency of the impressed oscillating current whereby to obtain the requisite degree of stabilization at various frequencies, such adjustment constituting one of the controls whereby the entire circuit arrangement may be readily adjusted to obtain maximum amplification at 80 various frequencies.

85 In witness whereof I have hereunto signed my name.

NEILSON RITTENHOUSE.
